RAILWAY TRAFFIC CONTROLLING
APPARATUS

Henry S. Young, Wilkinsburg, Pa., assignor to
The Union Switch & Signal Company, Swiss-
vale, Pa., a corporation of Pennsylvania

Application December 9, 1943, Serial No. 513,535

10 Claims. (Cl. 246—3)

My invention relates to railway traffic controlling apparatus, and particularly to manually controllable traffic direction controlling apparatus for at times directing traffic movements in one direction over a given stretch of railway track, and for at other times directing traffic movements in the opposite direction over the same stretch of track.

More specifically, my invention relates to traffic direction controlling apparatus controlled by a single manually operable traffic lever in conjunction with traffic controlled relays and manually operable signal control levers, for governing traffic movements in opposite directions over a main stretch of track which is connected, at a switch intermediate its ends, with an auxiliary track.

One feature of my invention is the provision of novel and improved means for directing traffic movements off of the auxiliary track and in a given direction over a portion of the main track stretch while another portion of the main track stretch is also occupied by a train moving in the opposite direction away from the switch.

A further feature of my invention is the provision of novel and improved indication means associated with the traffic direction controlling apparatus.

The apparatus of my invention is an improvement over that disclosed in a copending application for Letters Patent of the United States, Serial No. 412,279, filed September 25, 1941, by James J. Van Horn, for Railway traffic controlling apparatus now Patent No. 2,344,333, dated March 14, 1944. The apparatus of my invention is also an improvement over that disclosed in a copending application for Letters Patent of the United States, Serial No. 410,717, filed September 13, 1941, by James J. Van Horn for Railway traffic controlling apparatus.

I shall describe one form of apparatus embodying my invention, and shall then point out the novel features thereof in claims.

The accompanying drawings, Figs. 1a, 1b, 1c and 1d, when placed end to end, in that order, with Fig. 1a on the left, constitute a diagrammatic view showing one form of apparatus embodying my invention, in which Figs. 1a, 1b and 1c show a stretch of track, including a passing siding, provided with signals and train control apparatus for governing traffic movements in opposite directions over the stretch of track, and show manually controllable apparatus and traffic responsive apparatus for controlling the signals and train control apparatus; and Fig. 1d

shows apparatus which may be at a remote station such, for example, as a dispatcher's office, including a manually operable traffic lever and manually operable signal levers, for controlling the manually controllable apparatus shown in Figs. 1a, 1b and 1c, and also including indication apparatus.

Similar reference characters refer to similar parts in each of the drawings.

In each of the drawings, the contacts operated by the various relays and other control devices are identified by numbers, each such number having a distinguishing prefix from which it is separated by a dash when the associated contact is shown apart from the relay or other device by which it is operated, except when the associated contact is shown grouped with another contact of the same relay or other device having a distinguishing prefix. The prefix for each of these 20 contact numbers comprises the reference character for the respective relay or other device by which the associated contact is operated. For example, contact 8EK-154, shown in the upper right-hand corner of Fig. 1d, is identified by the number 154 separated by a dash from the prefix 8EK which is the reference character for relay 8EK by which this contact is operated.

Referring first to Figs. 1a, 1b and 1c, a stretch of main railway track Z is shown connected, at a switch S intermediate its ends, with an auxiliary track Y comprising a passing siding. Switch S may be of the well-known spring switch type which is biased to the normal position, in which it is shown in the drawings, for traffic movements 35 along the main track, but which is operable to the reverse position by a train moving from siding Y to track Z. The right-hand end of the stretch of track Z, as shown in the drawings, which I shall assume is the east end, is connected by a switch 5 with the east end of track Y. The west end of the stretch of track Z is connected, by a switch 4, with a second auxiliary track which may also be a passing siding. In order to simplify the drawings, each track, comprising two parallel series of track rails, is represented by a single line.

Track Z is divided into sections by insulated joints designated by the reference character 3. Beginning at the left-hand end of Fig. 1a, the 50 track sections are designated by the reference characters 1T, 2RT, 4WT, 4T, 6LT and 5T, respectively.

Each of these track sections is provided with one or more track circuits, each including a suitable source of direct current, such for example,

as a battery 7, connected across the rails adjacent one end of the section, and a track relay connected across the rails adjacent the opposite end of the section. Under some conditions, the current supplied to the rails by a battery 7 is coded, and under other conditions, this current is not coded. Beginning at the left-hand end of Fig. 1a, the track relays are designated by the reference characters 1R, 2RR, WR, ER, 4WR, 4R, 4ER, 6LR and 5R, respectively. Relays 2RR, WR, ER, 4WR, 4ER and 6LR are of the code following type.

Alternating current is also supplied to various track sections by transformers each designated by the reference character t, preceded by a distinguishing reference character, for controlling train-carried governing apparatus.

Traffic movements in the eastbound direction over track Z are governed by signals designated by the reference characters 2R, E and 6R, respectively, and traffic movements in the westbound direction over track Z are governed by signals designated by the reference characters 6L, W and 2L, respectively. Traffic movements from track Y over track Z in the westbound direction are governed by signal 4L.

Operated in conjunction with signal 6R is a contact 9 which is closed only when signal 6R is indicating caution or proceed. A signal repeater relay 6RP is controlled by this contact. Relay 2LP is similarly controlled in conjunction with the upper arm of signal 2L.

Relay 4LP is controlled by a contact 10, operated in conjunction with signal 4L, which is closed only when signal 4L is indicating stop.

Operated in conjunction with switch 5 is a contact 11 which, when switch 5 is in the normal position, completes a circuit for energizing a normal switch repeater relay 5NP, and which, when switch 5 is in the reverse position, completes a circuit for energizing a reverse switch repeater relay 5RP.

Two coding devices, designated by the reference characters 75 and 180, respectively, are located adjacent signal 6R. These coders are connected directly across terminals B and C of a suitable source of direct current, and therefore repeatedly close and open their contacts 12 and 13, respectively, at a suitable rate such, for example, as 75 and 180 times per minute, respectively. Similar coding devices, designated by similar reference characters, are located at the intermediate signal location comprising signals E and W, and at signal 2L.

A code following track circuit control relay 6LC is at times energized by current which is coded by the coding device 75 or by the coding device 180 adjacent signal 6R. At other times, relay 6LC is energized by steady current, or is deenergized. When relay 6LC is energized by coded current, the east end of section 6LT is supplied by battery 7 at signal 6R with current which is coded by contacts 99 and 100 of relay 6LC. When relay 6LC is energized by steady current, the east end of section 6LT is supplied with steady current from battery 7. When relay 6LC is deenergized, battery 7 is disconnected, at the front point of contact 99 of relay 6LC, from section 6LT, and the winding of relay 6LR is then connected across the rails of section 6LT through the back point of contact 99 of relay 6LC. The application of coded and steady direct currents to the west end of section 6LT, and to the ends of sections 4WT and 2RT, is similarly controlled by code following track circuit control relays 4EC, 4WC, EC, WC and 2RC, respectively.

Slow release repeater relays, controlled by front contacts of track relays, are designated by reference characters which are the same as the reference characters for the track relays by which they are controlled except that they include the letter F instead of the letter R. For example, the repeater for relay 6LR is designated 6LF.

Signal control relays, each of which is designated by the reference character B preceded by the reference character for the signal which it controls, are each controlled by a circuit including a back contact of an associated track relay and a front contact of the slow release repeater relay for that track relay. Each of the signal control relays 6LB, EWB and 2RB, in conjunction with its associated track relay, controls home and distant relays for its signal. The home relays are designated by the reference character H, and the distant relays are designated by the reference character D, each preceded by the reference character for its signal.

Home relay 4LH is controlled from the secondary winding of a signal transformer 4A through front and back points of the contact 109 of relay 4WR so as to respond when relay 4WR is being operated by current of either the 75 or the 180 code. Distant relay 4LD is controlled by contact 108 of relay 4WR in conjunction with the primary winding of transformer 4A, through a resonant rectifier decoding unit designated by the reference character 180DU, so as to respond only to 180 code.

Relays 2RH and 2RD for signal 2R, and relays 6LH and 6LD for signal 6L, are controlled similarly to relays 4LH and 4LD as indicated by the broken-line rectangles. In addition, relays 2RH and 2RD are controlled by relay 2RB, and relays 6LH and 6LD are controlled by relay 6LB.

Relays EWH and EWD are controlled by contacts of two track relays ER and WR and also by relay EWB.

A preparatory call-on stick relay 6LS is provided, which becomes energized when a westbound train passes signal 6L. Signal 6L can be controlled to display a call-on indication only if relay 6LS is energized. Relay 2RS for signal 2R is controlled similarly to relay 6LS.

Each of the signals is operated by circuits which include contacts of its home and distant relays, as shown for signal 4L.

Time locking stick relays 6LM, 4LM and 2RM for signals 6L, 4L and 2R, respectively, may be controlled similarly to the arrangement shown for controlling relay 4LM, which includes a time element relay 4TE.

A route stick relay 6WS becomes deenergized whenever signal 6L is cleared for a westbound traffic movement over switch 5 in the normal position, and stays deenergized until the train passes the intermediate signal W.

A slow pick-up track stick relay 4TS has a pick-up circuit controlled by relays 4R and 4LM, and has a stick circuit controlled by only relay 4R.

Eastbound and westbound directional stick relays ES and WS, respectively, at the location of intermediate signals E and W, are controlled to become energized when signal E or signal W, respectively, is controlled to display an indication other than stop, and are then retained in the energized condition while the block for the associated signal is occupied.

Relay LR may control the lighting of signals E and W. Relay LR also, in conjunction with relays ES and WS, controls the energization of train control transformers Wt and Et, respectively.

A polarized reverse traffic relay ESP becomes

energized by current of reverse polarity when signal 2R is controlled to indicate stop after an eastbound train has left section 2RT but before it has left section 6LT.

When the eastbound train enters section 6LT, deenergizing relay 4EF, a polarized storage control and traffic indication relay ESP which, as shown in the drawings, is energized by current of reverse polarity, becomes energized by current of normal polarity in a circuit including a front contact of relay ESP. The main function of relay ESP is to control the storage of control for a polarized signal control relay 4LHS for controlling leave siding signal 4L. Relay ESP is controlled over a front contact of relay 6WS and a back contact of relay 6LS in order to prevent the storage of control for relay 4LHS for clearing signal 4L while signal 6L is clear or the time locking is effective, or while a westbound train which has passed signal 6L is occupying the main line between signal 6L and signal W. The circuits for relay 4LHS are so arranged that relay 4LHS can become energized by current of either normal or reverse polarity over conductors 181 and 182, but can become energized by current of only normal polarity over conductors 181 and 183.

Referring now to Fig. 1d, control and indication apparatus are shown in a control station which may, for example, be a dispatcher's office, for manually controlling the signals and traffic direction control apparatus shown in Figs. 1a, 1b and 1c, and providing indications of the condition of various parts of the apparatus shown in Figs. 1a, 1b and 1c. I shall assume that the control of the signals and traffic direction control apparatus in Figs. 1a, 1b and 1c by the manually operable apparatus shown in Fig. 1d, and the control of the indication apparatus in Fig. 1d by the various parts of the apparatus shown in Figs. 1a, 1b and 1c are effected through code control equipment of the time code type shown and described in Letters Patent of the United States No. 2,229,249, granted January 21, 1941, to Lloyd V. Lewis for Remote control systems.

Apparatus represented in Fig. 1d by a rectangle designated by the legend "Office Code Equipment", in response to operation of manually controllable signal levers 2V, 4V and 6V and a traffic lever 8V, effects the transmission of control current at various codes over a single pair of line conductors designated by the reference characters 1U and 2U to field code equipment located adjacent switch 5 and also to field code equipment adjacent switch 1 for controlling polarized signal control relays designated by the reference characters 2RHS, 4LHS and 6LHS and polarized traffic direction control relays designated by the reference characters 8WFS and 8EFS. These signal control relays and traffic direction control relays are of the stick polar type, that is, their polar contacts remain closed in either position until current is supplied to operate them to the opposite position.

The field code equipments, in response to control by various parts of the apparatus shown in Figs. 1a, 1b and 1c, effect the transmission of indication current at various codes over the same pair of line conductors 1U and 2U to the office code equipment for energizing a delivery relay D and controlling clear signal indication relay 4LK, reverse traffic indication relay 4EK, westbound traffic control relay 4LZ, leave siding indication relay 8EK, and block indication relays 8ETK and 8WTK.

The means in the control station for effecting

control of the signal and traffic control relays through the office and field code equipments is designated, for each of these relays, by the reference character for the relay followed by the word "control." For example, the legend "6LHS control", associated with the dash line extending from lever 6V to the office code equipment, means that the normal and reverse control circuits for energizing relay 6LHS are controlled by lever 6V.

Similarly, each of the control circuit portions at each field code equipment station, for effecting control of one of the various relays in the control station, is designated by the reference character for the relay, followed by the abbreviation "cont." for the word "control."

Traffic lever 8V in the control station is of a type which combines, with traffic control contacts, a starting push-button for controlling starting relays for the code equipment, designated by the reference characters 2ST and 6ST.

A main traffic control relay 8LP, of the stick polar type, becomes energized by current of normal polarity in a circuit including a contact designated 8E of lever 8V for controlling relays 8EFS and 8WFS for eastbound traffic movements, and becomes energized by current of the opposite polarity in a circuit including a contact, designated 8W, of lever 8V for controlling relays 8WFS and 8EFS for westbound traffic movements.

Eastbound and westbound traffic indication relays 8EFK and 8WFK, respectively, in the control station, are also controlled in part by relay 8LP.

A track model is shown in Fig. 1d, on which the track and signal layout of Figs. 1a, 1b and 1c is represented. Indication lights are located in the track model, including eastbound and westbound traffic indication lights 8EKK and 8WKK, respectively, a block indication light BK, and a leave siding indication light 8ESK.

Having described, in general, the arrangement and control of the apparatus shown by the accompanying drawings, I shall now describe, in detail, its operation.

As shown in Fig. 1d, traffic lever 8V is in the position for effecting operation of the polar contacts of traffic direction control relays 8EFS and 8WFS to the left-hand position to provide for westbound traffic movements, but the signal control levers are in the normal position, and hence all signals are indicating stop. Switches 1, S and 5 are in the normal position, shown in the drawings.

With switch 5 occupying the normal position, relay 5NP is energized by a circuit passing from terminal B, through contact 11 of switch 5, and the winding of relay 5NP to terminal C. Track relays 4R, 4R and 5R are energized. With signal 4L indicating stop, relay 4LP is energized by a circuit passing from terminal B, through contact 10 of signal 4L, and the winding of relay 4LP to terminal C. Relay 2LP is energized by a similar circuit. With relay 4LP energized, a polarized signal indication relay 4LPP is energized by current of reverse polarity in a circuit passing from terminal B, through the back point of contact 18 of relay ESP, contact 4LP-19, winding of relay 4LPP, and the back point of contact 20 of relay ESP to terminal C.

Also, with relay 4LP energized, relay 4LM is energized by a stick circuit passing from terminal B, through the back point of contact 4LSP-22, contact 4LP-23, the front point of contact 25 of relay 4LM, and the winding of relay

4LM to terminal C. Relays 2RM and 6LM are similarly energized. With relay 4LM energized, a pick-up circuit is completed for relay 4TS, passing from terminal B, through contact 14 of relay 4R, contact 4LM-15, and the winding of relay 4TS to terminal C. A stick circuit is also completed for this relay, which includes contact 16 of relay 4TS instead of contact 4LM-15 in the pick-up circuit just traced.

With relay 6LM energized, a stick circuit is completed for relay 6WS, passing from terminal B, through contact 27 of relay 6LM, contact 32 of relay 6WS, and the winding of relay 6WS to terminal C.

With traffic lever 8V in the westbound traffic controlling position, relay 8LP has last previously been energized by current of reverse polarity for operating its polar contacts to the right-hand position, as shown in the drawings.

A pick-up circuit is therefore closed for energizing relay 8WFK, passing from terminal B, through contact 8LP-33 in the right-hand position, contact 8WTK-34, and the winding of relay 8WFK to terminal C. A stick circuit is also completed for this relay which is the same as the pick-up circuit just traced except that it includes contact 36 of relay 8WFK instead of contact 8WTK-34.

With relay 8WFK energized, the westbound traffic indication lamp 8WKK is lighted by a circuit passing from terminal B, through contact 8WFK-121, and lamp 8WKK to terminal C.

Also, with relay 8WFK energized, relay 8WTK is energized by a stick circuit passing from terminal B, through contact 8WFK-37, contact 38 of relay 8WTK, the back point of contact 39 of relay D, and the winding of relay 8WTK to terminal C.

With contact 8LP-33 occupying the right-hand position, relays 8EFS and 8WFS have last previously been energized by current of normal polarity for operating their polar contacts to the left-hand position, shown in the drawings.

With the signal levers in the normal position, the contacts of relays 6LHS, 4LHS and 2RHS are also in the left-hand position, for controlling the corresponding signals to indicate stop.

With the polar contacts of relays 6LHS and 8EFS occupying the left-hand position, relay 6LC is energized by steady current in a circuit passing from terminal B, through contact 6LHS-40, contact 8EFS-41 closed in the left-hand position, contact ESPP-42 closed in the right-hand position, contact 6WS-43, contact 44 of relay 6LS, contacts 5R-45 and 6LM-46, and the winding of relay 6LC to terminal C. With relay 6LC steadily energized, steady current is supplied from battery 7 to the east end of section 6LT by a circuit which includes contacts 99 and 100 of relay 6LC and the secondary winding 102 of transformer 6LT. Relay 4ER at the west end of section 6LT is connected across the rails through the back point of contact 99 of relay 4EC, and is therefore energized by steady current which is supplied to the east end of this section. With relay 4ER energized, relay 4EF is energized by a circuit passing from terminal B, through contact 48 of relay 4ER, and the winding of relay 4EF to terminal C.

With relay 4EF energized, relay ESPP is energized by current of reverse polarity in a circuit passing from terminal B, through the front point of contact 4EF-49, winding of relay ESPP, and contacts 6LS-50, 6WS-51, 6LF-52, and contact 53 of relay 4EF, to terminal C.

With relay 4ER energized by steady current, relay 4WC is also energized by steady current in a circuit passing from terminal B, through contact 54 of switch S, contact 55 of relay 4TE, contact 56 of relay 4LM, contacts 4R-57 and 4LSP-58, contact 59 of relay 4ER, back point of contact 4WS-60, and the winding of relay 4WC to terminal C. Steady or non-coded current is therefore supplied to the east end of section 4WT, from battery 7 at this location, through the front point of contact 99 of relay 4WC, contact 100 of this relay, and the secondary winding 102 of transformer 4WT. Relay ER at the west end of this section is therefore energized by non-coded current passing through the back point of contact 99 of relay EC.

With relay ER energized, relay EF is energized by current passing from terminal B, through the front point of contact 61 of relay ER, and the winding of relay EF to terminal C. With relay EF energized, relay WC is energized by non-coded current passing from terminal B, through contact 62 of relay EF, back point of contact ES-63, contact 64 of relay WS, and the winding of relay WC to terminal C. Relay 2RR at the west end of section 2RT is therefore energized by non-coded current passing through the back point of contact 99 of relay 2RC. With relay 2RR energized, relay 2RF is energized by a circuit passing from terminal B, through contact 65 of relay 2RR, and the winding of relay 2RF to terminal C.

With the apparatus controlled by lever 8V thus arranged for a westbound traffic movement, I shall assume that the dispatcher decides to clear signal 4L to permit a train to leave siding Y. He will therefore reverse lever 4V for energizing relay 4LHS by current of reverse polarity in a circuit including conductors 181 and 182, contact 8EFS-67 closed in the left-hand position, and the front point of contact ESPP-66. With relay 4LHS thus energized by current of reversed polarity, its polar contact 4LHS-68 will be closed in the right-hand position, thereby completing a circuit for energizing relay 4LSP, passing from terminal B, through contacts 4LHS-68, 6WS-69 and 6LS-70, and the winding of relay 4LSP to terminal C. Relay 4LSP, upon becoming energized, opens the stick circuit for relay 4LM previously traced, thereby causing relay 4LM to become deenergized.

Relay 4LSP, upon becoming energized, also opens, at its contact 4LSP-58, the circuit previously traced for relay 4WC, causing this relay to become deenergized.

With relay 4WC deenergized, battery 7 is disconnected, at contacts 99 and 100 of relay 4WC, from the east end of section 4WT, and hence relay ER at the west end of this section becomes deenergized, causing relay EF to also become deenergized. With relay EF deenergized, the circuit previously traced for relay WC is opened at contact 62 of relay EF, and hence the current is disconnected from the east end of section 2RT, causing relay 2RR, and in turn relay 2RF, to also become deenergized.

With relay 2RF deenergized, relay 2RC will now be energized by coded current having a frequency of 180 or 75 times per minute according as relay 2LP is energized or deenergized. Assuming that relay 2LP is deenergized, the circuit for relay 2RC passes from terminal B, through contact 12 of coding device 15, back point of contact 71 of relay 2LP, contact 2RF-72, contact 8WFS-73 in the left-hand position, contact 74 of relay 2RS, contact 175 of relay 2RM, contact 1R-176,

and the winding of relay 2RC to terminal C. At the same time, a circuit will be completed for supplying alternating current to the primary winding 101 of train control transformer 2t, this circuit passing from terminal X of a suitable source of alternating current, through contact 8WFS-77, contact 78 of relay 2RF, and primary winding 101 of transformer 2t to terminal O of the same source of alternating current.

Direct current from battery 7 and alternating current from secondary winding 102 of transformer 2t, each periodically interrupted 75 times per minute, will therefore now be supplied to the west end of section 2RT through the front points of contacts 99 and 100 of relay 2RC. Relay WR at the east end of section 2RT will therefore now respond to the coded direct current at a corresponding frequency, and will therefore alternately close its contact 79 at the front and back points. While contact 79 of relay WR is closed at its front point, relay WF, which is slow releasing, will become energized, and will then retain its contacts closed at the front points during the intervals between the closed periods of the front point of contact 79.

During the periods when contact 79 of relay WR is closed at its back point, relay EWB will be energized by a circuit passing from terminal B, through the back point of contact 79 of relay WR, front point of contact 124 of relay WF, back point of contact 123 of relay EF, and the winding of relay EWB to terminal C. Relay EWB, being of the slow releasing type, will retain its contact closed during the intervals between the successively closed periods of the back point of contact 79 of relay WR.

Signal transformer EWA will therefore be energized by a circuit including contact 80 of relay EWB, the back points of contacts 81 and 82 of relays WR and ER, respectively, and by a circuit including contact 80 of relay EWB and the front point of contact 81 of relay WR, alternately. Since the current supplied to section 2RT is at a code frequency of 75 times per minute, relay EWD will not respond, but relay EWH will be energized by one circuit including the back point of contact 88 of relay WR and the back point of contact 88 of relay ER, and by another circuit including the front point of contact 89 of relay WR.

With relays WF and EWH energized, relay WS becomes energized by a circuit passing from terminal B, through contact 90 of relay EWH, back point of contact 91 of relay EF, front point of contact 92 of relay WF, and the winding of relay WS to terminal C. With relay EWH energized, relay LR is also energized by a circuit passing from terminal B, through contact 103 of relay EWH, and the winding of relay LR to terminal C. With relay EWH energized, signal W will now be operated to the caution position and will become lighted on account of relay LR being energized. With relays WS and EWH energized, relay EC will now become energized by current of the 180 code passing from terminal B, through contact 13 of coder 180, front point of contact 95 of relay EWH, contact 96 of relay EF, front point of contact 97 of relay WS, contact 98 of relay ES, and the winding of relay EC to terminal C. With relays LR and WS energized, the train control transformer Et will be energized by a circuit passing from terminal X, through contacts 105 and 107 of relays LR and WS, respectively, and primary winding 101 of transformer Et to terminal O.

Coded direct current from battery 7 and coded alternating current from transformer Et will now be supplied to the west end of section 4WT through the front point of contact 99 of relay EC and through contact 100 of relay EC. The current supplied to the west end of section 4WT being coded at the 180 frequency, relay 4WR at the east end of section 4WT will now become energized by current of this frequency through the back point of contact 99 of relay 4WC.

With relay 4WR energized by coded direct current of the 180 code, relays 4LH and 4LD will become energized, causing the operation of the arm of signal 4L to the proceed position, by a circuit passing from terminal B, through the front point of contact 4LSP-22, contacts 4LM-112 and 4TS-113, contact 114 of relay 4LH, front point of contact 115 of relay 4LD, mechanism 4LG of signal 4L, and the front point of contact 116 of relay 4LD to terminal C. At the same time, train control transformer 4Lt will be energized by a circuit passing from terminal X, through contact 4LH-110, contact 111 of relay 4WR, and primary winding 101 of transformer 4Lt to terminal O.

With signal 4L now indicating proceed, relay 4LP controlled by contact 10 of this signal will be deenergized, causing relay 4LPP to also become deenergized. With relay 4LPP deenergized, a circuit including the back point of contact 156 of relay 4LPP will cause a code to be transmitted for effecting the energization of clear signal indication relay 4LK through the front point of contact 178 of delivery relay D. With relay 4LK energized, indication lamp 4LKK adjacent lever 4V will become energized over a circuit including contact 184 of relay 4LK.

When the train leaves siding Y, passing signal 4L and entering section 4T, relay 4R will become deenergized, causing relay 4TS to become deenergized, which then causes the arm of signal 4L to return to the stop indication.

The dispatcher will now return lever 4V to the normal position, thereby causing relay 4LHS to become energized by current of normal polarity over conductors 181 and 182, and contact 4LHS-68 will therefore open the circuit previously traced for relay 4LSP, causing this relay to become deenergized. With relays 4LSP and 4TS deenergized, relay 4LM will become energized by its pick-up circuit passing from terminal B, through the back point of contact 4LSP-22, contacts 4LP-23 and 4TS-24, and the winding of relay 4LM to terminal C. With relay 4LM energized, relay 4TS, after the train leaves section 4T, will again become energized by its pick-up circuit previously traced.

I shall assume that, after the train leaves section 4T at the west end of the stretch of track 60 Z, the dispatcher decides to arrange for an east-bound traffic movement. He will, therefore, operate lever 8V to the position for opening contact 8W and closing contact 8E in the circuits for relay 8LP. With contact 8E closed, relay 8LP will become energized by a circuit passing from terminal B, through push-button contact 119 of lever 8V, contact 8WTK-120, contact 8E of lever 8V, and the winding of relay 8LP to terminal C. Contact 8LP-33 of relay 8LP will now move to the left-hand position, thereby opening the circuits previously traced for relay 8WFK, and causing relay 8WFK to become deenergized. With contact 8LP-33 closed in the left-hand position, the E control for relays 8EFS and 8WFS 75 will cause a code to be transmitted to the field

equipments for energizing relays 8EFS and 8WFS for operating their contacts to the right-hand position.

Relay 8WFK, upon becoming deenergized, causes relay 8WTK to become deenergized because contact 8WFK-37 is now open. Also, with relay 8WFK deenergized, westbound traffic indication light 8WKK will become deenergized on account of the opening of contact 8WFK-121.

The circuit previously traced for constantly energizing relay 6LC at signal 6R will now be open at contact 8EFS-41, and a circuit will be completed at signal 2R for energizing relay 2RC by constant current, this circuit passing from terminal B, through contact 2RHS-122, contact 8WFS-73 closed in the right-hand position, contact 74 of relay 2RS, contact 175 of relay 2RM, contact 4R-176, and the winding of relay 2RC to terminal C. With relay 2RC constantly energized, non-coded current will be supplied to the west end of section 2RT by a circuit including contacts 99 and 100 of relay 2RC. Relay WR will therefore be constantly energized by current received from the east end of section 2RT through the back point of contact 99 of relay WC. With relay WR energized, relay WF will become energized by its circuit previously traced, thereby causing steady current to now energize relay EC in a circuit passing from terminal B, through contact 125 of relay WF, back point of contact 97 of relay WS, contact 98 of relay ES, and the winding of relay EC to terminal C.

With relay EC energized by non-coded current, non-coded current will be supplied to the west end of section 4WT, causing relay 4WR at the east end of this section to now be steadily energized. With relay 4WR steadily energized, relay 4EC will be steadily energized by a circuit passing from terminal B, through contact 54 of switch S, contacts 55 and 56 of relays 4TE and 4LM, respectively, contacts 4R-57, 4LSP-58 and 4WR-126, winding of relay 4EC, and contact 4WS-127 to terminal C.

Constant current will therefore be supplied to the west end of section 6LT through contacts 99 and 100 of relay 4EC, causing relay 6LR at the east end of this section to also be steadily energized. Relay 6LF will therefore be energized by a circuit passing from terminal B, through contact 128 of relay 6LR, and the winding of relay 6LF to terminal C.

With relay 6LF energized, a field code equipment circuit including contacts 185 of relay 8EFS and 6LF-186 will be completed for causing code to be transmitted to the office code equipment for energizing block indication relay 8ETK by a circuit including the front point of contact 189 of delivery relay D. With relay 8ETK energized, a circuit will be completed for energizing relay 8EFK, this circuit passing from terminal B, through contact 8LP-33 closed in the left-hand position, contact 8ETK-129, and the winding of relay 8EFK to terminal C. Relay 8EFK, upon becoming energized, completes its stick circuit which is the same as the pick-up circuit just traced except including contact 130 of relay 8EFK instead of contact 8ETK-129. With relay 8EFK energized, the eastbound traffic indication light 8EKK will be lighted by a circuit passing from terminal B, through contact 8EFK-131, and lamp 8EKK to terminal C.

The dispatcher will now operate lever 2V for reversing relay 2RHS, which opens contact 2RHS-122 in the circuit for steadily energizing relay 2RC. Relay 2RC, upon becoming deener-

gized, causes the successive deenergization of relays WR, WF, EC, 4WR, 4EC, 6LR and 6LF, in that order. With relay 6LF deenergized, relay 6LC will now become energized by coded current of 180 or 75 frequency according as relay 6RP is energized or deenergized. If relay 6RP is deenergized, relay 6LC will be energized by current of the 75 code passing from terminal B, through contact 12 of coding device 75, back point of contact 6RP-132, contact 6LF-133, contact 8EFS-41 closed in the right-hand position, contact 8SPP-42 closed in the right-hand position, contact 6WS-43, contact 44 of relay 6LS, contacts 5R-45 and 6LM-46, and the winding of relay 6LC to terminal C. At the same time, a circuit will be closed for energizing primary winding 101 of train control transformer 6Lt, this circuit passing from terminal X, through contacts 8EFS-134, and 6LF-135, and primary winding 101 to terminal O.

Direct current from battery 1 and alternating current from secondary winding 102 of transformer 6Lt, coded at a frequency of 75 times per minute, will now be supplied to the east end of section 6LT through the front point of contact 99 and contact 100 of relay 6LC. Relay 4ER at the west end of section 6LT will therefore now respond to coded direct current of the 75 code frequency received from the west end of section 6LT through the back point of contact 99 of relay 4EC. Relay 4WC will therefore now be energized by direct current coded at the same frequency, in its circuit previously traced. During the de-energized periods of relay 4ER, train control transformer 4t will be energized by a circuit passing from terminal X, through contact 147 of relay 4ER, contact 148 of relay 4EF, and primary winding 101 of transformer 4t to terminal O. With relay 4EF energized, relay 8SPP will again become energized by its circuit previously traced.

With contact 8EFS-67 now closed in the right-hand position, relay 4LHS cannot become energized in the reverse direction over conductors 181 and 182, but can only become energized in the normal direction over conductors 181 and 183.

With relay 4WC now being operated by the 75 code current, coded direct current and train control current will be supplied at this frequency to the east end of section 4WT. Relay ER at the west end of section 4WT will therefore now respond to current of the 75 code, causing relay EF to be periodically energized at this frequency, through a circuit passing from terminal B, through the front point of contact 61 of relay ER, and the winding of relay EF to terminal C.

Relay EWB will now be energized by a circuit passing from terminal B, through the back point of contact 61 during the deenergized periods of relay ER, front point of contact 123 of relay EF, back point of contact 124 of relay WF, and the winding of relay EWB to terminal C. Relay EWH will therefore now be controlled by circuits including the back point of contact 81 of relay WR and the front and back points of contact 82 of relay ER, which energize transformer EWA and cause energy to be supplied to circuits through the back point of contact 89 of relay WR and the front and back points of contact 88 of relay ER for energizing relay EWH. The arm of signal E will therefore be operated to display the caution indication.

With relays EWH and EF energized, relay ES will become energized by a circuit passing from terminal B, through contact 98 of relay EWH, back point of contact 92 of relay WF, front point

of contact 94 of relay EF, and the winding of relay ES to terminal C. Relay LR will now become energized by its circuit previously traced. Relay WC will now become energized by current of 180 code passing from terminal B, through contact 13 of coder 186, front point of contact 95 of relay EWH, contact 136 of relay WF, front point of contact ES-63, contact 64 of relay WS, and the winding of relay WC to terminal C. The primary winding 101 of train control transformer Wt will now be energized by a circuit passing from terminal X, through contact 106 of relay LR, contact 137 of relay ES, and primary winding 101 of transformer Wt to terminal O. With current of the 180 code supplied to the east end of section 2RT on account of relay WC being energized by current of that code, relay 2RR will operate its contacts at this frequency, causing relay 2RF to become energized by its circuit previously traced.

Relay 2RB will now become energized by a circuit passing from terminal B, through contact 138 of relay 8WFS, contact 139 of relay 2RF, contact 140 of relay 2RR, and the winding of relay 2RB to terminal C. With contact 141 of relay 2RB thus closed, and with relay 2RR responding to coded current of the 180 frequency, relays 2RH and 2RD will both become energized, causing the mechanism of signal 2R to become energized by a circuit including contact 2RHS-141, contact 142 of relay 2RH, and front points of contacts 143 and 144 of relay 2RD for operating the arm of signal 2R to the proceed position.

I shall now assume that an eastbound train passes signal 2R, deenergizing, in succession, relays 1R, 2RR, ER, 4R and 4ER. Relay 2RR, upon becoming deenergized, causes relay 2RF to become deenergized which, in turn, causes relay 2RB to become deenergized. Relays 2RH and 2RD, upon then becoming deenergized, cause the arm of signal 2R to again display the stop indication. With relay ER deenergized, relay EF will become deenergized and cause relay EWB, and in turn relay EWH, to become deenergized.

With relay EF deenergized, relay ES will now remain energized by a stick circuit passing from terminal B, through contact 145 of relay EF, contact 146 of relay ES, and the winding of relay ES to terminal C. With relay 4ER deenergized, relay 4WC will now be deenergized, causing the interruption of direct current from battery 7 and train control current from transformer 4Wt being supplied to the east end of section 4WT. With relay 4ER deenergized, relay 4EF will also be deenergized, causing the interruption of the train control current from transformer 4t to the east end of section 4T.

If, now, the dispatcher decides to arrange the apparatus to permit a train to leave siding Y while section 6LT is occupied by the eastbound train, he will restore lever 2V to the normal position for causing the contacts of relay 2RHS to again be closed in the left-hand position. A circuit will, therefore, be completed for steadily energizing relay 2RC, this circuit passing through contact 2RHS-122, as previously traced. Relays 2RR, 2RF, 2RB and 2RH will therefore be deenergized, and relays WR and WF will be energized.

With relay WF energized, relay ESP will become energized by current of reverse polarity in a circuit passing from terminal B, through contact 161 of relay WF, contact 162 of relay ES, back point of contact 163 of relay WS, winding of relay ESP, and the back point of contact

WS-164 to terminal C. Relay ESPP will then become energized by current of normal polarity passing from terminal B, through contact 179 of relay ESP, back point of contact 53 of relay 4EF, contacts 6LF-52, 6WS-51 and 6LS-50, winding of relay ESPP, and the back point of contact 4EF-49 to terminal C. A circuit including contacts ESPP-149 and ESPP-150 will therefore now be closed for causing the field code equipment adjacent signal 6R to transmit a code to the office code equipment for energizing relay 8EK by a circuit including the front point of contact 153 of delivery relay D. With relay 8EK energized, a circuit will be completed for lighting lamp 8ESK to inform the dispatcher that he may now reverse traffic lever 8V preparatory to clearing signal 4L to permit a westbound train to leave the siding.

I shall now assume that the dispatcher returns lever 8V to the position for arranging for a westbound traffic movement. Relay 8LP will therefore become energized by a circuit passing from terminal B, through push-button contact 119 associated with lever 8V, contact 8EK-155, contact 8W of lever 8V, and the right-hand portion of the winding of relay 8LP to terminal C.

Upon the operation of contact 8LP-33 to its right-hand position, relay 8EFK will become deenergized, causing eastbound traffic indication light 8EKK to become extinguished. The deenergization of relay 8EFK opens contact 8EFK-187 in the stick circuit for relay 8ETK, which is, however, already deenergized on account of relay 6LF having become deenergized. The deenergization of relay 8EFK also opens the stick circuit for relay 8EK including contact 8EFK-151, contact 152 of relay 8EK, and the back point of contact 153 of delivery relay D.

With contact 8WFS-73 now in the left-hand position, relay 2RC will become energized by coded current in the circuit previously traced. Relay WR will therefore now be periodically energized in response to this current, causing relay WF and also relay EWB to become energized, as previously described. With relays WF and EWH now energized, relay WS will become energized by its pick-up circuit previously traced.

With relay WS energized, relay ESP will now become energized by current of normal polarity in a circuit which is the same as the circuit previously traced for this relay except that it includes the front points of contacts 163 of relay WS and WS-164 instead of the back points of these contacts. Relay 4LPP will therefore now be energized by current of normal polarity in a circuit passing from terminal B, through contact 21 of relay ESP in the left-hand position, front point of contact 20 of relay ESP, winding of relay 4LPP, contact 4LP-19, front point of contact 13 of relay ESP, and contact 17 of relay ESP in the left-hand position to terminal C. A circuit will now be completed, including contact 156 of relay 4LPP and contact 157 of this relay in the left-hand position, for the field code equipment adjacent signal 6R, causing coded current to be transmitted to the office code equipment for energizing relay 4LZ by a circuit including the front point of contact 160 of relay D.

Relay 8WFK will now become energized by a circuit passing from terminal B, through contact 8LP-33 closed in the right-hand position, contact 4LZ-35, and the winding of relay 8WFK to terminal C. With relay 8WFK energized, the westbound traffic indication light 8WKK will be lighted by its circuit previously traced. This in-

dicates to the dispatcher that he may now transmit a code for clearing signal 4L, or he may return the traffic control to the eastward direction if he finds that he must advance another eastbound train past signal 2R before permitting the westbound train to leave the siding.

With relay 8WFK energized, block indication lamp BK will also become lighted by a circuit passing from terminal B, through contacts 8WFK-196, 8WTK-198 and 8ETK-199, and lamp BK to terminal C.

If the dispatcher should decide to restore traffic control to the eastbound direction, he will reverse traffic lever 8V to the position for closing its contact 8E. Relay 8LP will now become energized by a circuit passing from terminal B, through contact 119 of the push-button associated with lever 8V, contact 4LZ-173, contact 8E, and the left-hand portion of the winding of relay 8LP to terminal C. Relays 8WFK and 4LZ will therefore become deenergized, causing lamps BK and 8WKK to become extinguished, and an office code circuit will be completed for causing the energization of relays 8EFS and 8WFS to again operate their contacts to the right-hand position.

Relay 2RC will therefore now again become energized by steady current, as previously described, causing relays WR and WF to also again become energized by steady current, and hence relays EWB and EWH will become deenergized. Relay WS will therefore also become deenergized.

Relay ESP will again become energized by current which moves its contacts to the right-hand position. Relay 4LPP will therefore now be energized by a circuit including contacts 17 and 21 of relay ESP in the right-hand position, which causes the contacts of relay 4LPP to also occupy the right-hand position. With relay ESPP energized by current of normal polarity, relay 8EK will be energized because of the completion of a circuit at the field code equipment including contacts 149 and 150 of relay ESPP. With relay 8EK energized, relay 8EFK will now become energized by a circuit passing from terminal B, through contact 8LP-33 closed in the left-hand position, contact 8EK-190, and relay 8EFK to terminal C. With relay 8EFK energized, lamp 8EKK will again become lighted and relay 8EK will be retained in the energized condition by its stick circuit previously described. Also, with relay 8EFK energized, lamp BK will become lighted by a circuit passing from terminal B, through contacts 8EFK-197, 8WTK-198 and 8ETK-199, and lamp BK to terminal O.

The dispatcher may now again reverse lever 2V for reversing relay 2RHS.

If, instead of restoring the traffic direction control apparatus to provide for eastbound traffic movements, the dispatcher had decided to permit a train to leave siding Y, he would have kept traffic lever 8V in the position for controlling westbound traffic movements and, upon the lighting of the westbound traffic indication light, he would have moved lever 4V to the position for causing relay 4LHS to be energized by current of reverse polarity. Relay 4LSP would then become energized by the circuit previously traced.

With relay 4LSP energized, and with relay ESP energized by current of normal polarity, a signal stick relay 4WS will become energized by a circuit passing from terminal B, through contacts 165 and 166 of relay ESP, contact 4LSP-167, and the winding of relay 4WS to terminal C. Relay

4WS, upon becoming energized, will complete its own stick circuit passing from terminal B, through contact 168 of relay 4WS, contact 4LSP-167, and the winding of relay 4WS to terminal C.

With relay 4WS energized, a circuit is completed for energizing relay 4WC by non-coded current passing from terminal B, through contact ESP-191, front point of contact 4WS-60, and the winding of relay 4WC to terminal C. With relay 4WC energized by non-coded current, relay ER at the west end of section 4WT will also be energized by non-coded current, causing relay EF to become energized.

With relay EF energized, relay ES will become deenergized on account of contact 145 of relay EF being opened in the stick circuit for relay ES. With relay ES deenergized, relay ESP will become deenergized. With relay ESP deenergized, relay 4WC becomes deenergized because of the opening of contact ESP-191. Relays ER and EF at the intermediate location will therefore now become deenergized. Relay EC will then become energized by coded current in the circuit previously traced. Signal 4L will now become operated to display the proceed indication, as previously described.

With relay 4WS energized, relay ESPP is retained in the normal energized condition. When the train on siding Y passes signal 4L, entering section 4T, relay 4TS will become deenergized and cause signal 4L to again display the stop indication. Relay 4LPP will then again become energized by current of reverse polarity, causing its polar contacts to occupy the right-hand position. A field code equipment circuit will then become closed, including contact 156 of relay 4LPP, contact 157 of relay 4LPP in the right-hand position, and contacts 193 and 194 of relay ESPP, for effecting energization of relay 4EK in the control station. Stop indication lamp 4EKK will then become lighted by a circuit including contact 195 of relay 4EK. With relay ESPP in the normal energized condition, train control transformer 6LT will remain energized by a circuit including contact ESPP-192 after contact 8EFS-134 has been opened.

Relay 6LC will also be retained in a periodically energized condition by a circuit which includes contact ESPP-42 in the left-hand position after contact 8EFS-41 moves to the left-hand position. When the eastbound train leaves section 6LT, the coded energy supplied to the east end of section 6LT causes relay 4ER, and in turn relay 4EF, to become energized. Relay ESPP will therefore again become energized by current of reverse polarity, and will then again complete the circuit for energizing relay 6LC by non-coded current.

Emergency control circuits are provided in the control station for energizing relay 8LP in the original direction if the dispatcher should attempt to reverse traffic, but the corresponding block indication relay did not become energized. If, for example, the dispatcher should move lever 8V to the position for energizing relay 8LP for eastbound traffic movements, and relay 8ETK should fail to become energized, he may restore relay 8LP to the condition shown in Fig. 1d by means of a circuit passing from terminal B, through push-button contact 119 of lever 8V, contacts 8EFK-201 and 8WFK-202, back point of contact 8ETK-203, contact 8W of lever 8V, and the right-hand portion of the winding of relay 8LP to terminal C.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In railway traffic direction controlling apparatus controlled by manually operable traffic apparatus for governing traffic movements in both directions over a main track stretch connected at a switch intermediate its ends with an auxiliary track, including a signal for governing traffic movements in a given direction off of said auxiliary track and over a given portion of said main track which is in said given direction from said switch, the combination comprising, a directional stick relay, a pick-up circuit closed for energizing said stick relay when said traffic apparatus is operated for governing traffic movements in the opposite direction over said main track stretch, a stick circuit for then retaining said stick relay energized while said main track stretch is occupied by a train moving in said opposite direction, a second directional stick relay, a pick-up circuit closed for energizing said second stick relay when said traffic apparatus is operated for governing traffic movements in said given direction over said given portion of said main track while said first stick relay is still energized by its stick circuit because of said train occupying said main track stretch in said opposite direction from said switch, and means including front contacts of said first and second directional stick relays for clearing said signal while said main track stretch is still occupied by said train in said opposite direction from said switch.

2. In railway traffic direction controlling apparatus controlled by manually operable traffic apparatus for governing traffic movements in both directions over a main track stretch connected at a switch intermediate its ends with an auxiliary track, including a signal for governing traffic movements in a given direction off of said auxiliary track and over a given portion of said main track which is in said given direction from said switch and between said switch and a second signal for governing traffic movements in said given direction, the combination comprising, a normally energized route stick relay, a third signal for governing traffic movements in said given direction along said main track stretch and over said switch toward said second signal, means for deenergizing said route stick relay if said third signal is controlled to display a caution or proceed indication and for retaining said route stick relay deenergized until a train governed by said third signal passes said second signal, a polarized relay, means controlled by said polarized relay if energized by current of reverse polarity for clearing said first signal, and manually controllable means for energizing said polarized relay by current of normal or reverse polarity if said route stick relay is energized but for energizing said polarized relay by current of only normal polarity if said route stick relay is deenergized.

3. In railway traffic direction controlling apparatus for governing traffic movements in both directions over a given stretch of track divided into a first and a second and a third section arranged in that order, including a given signal for governing traffic movements in a given direction

onto said stretch through said first section, the combination comprising, a directional stick relay, a pick-up circuit for energizing said directional stick relay if said apparatus is arranged for a traffic movement in said given direction into said second section, a stick circuit for then retaining said directional stick relay energized while a train moves through said second and third sections, a reverse traffic indication device, a contact arranged to become closed if said signal is controlled to indicate stop after said train has left said first section but before said train has left said third section, and a circuit including said contact and a front contact of said stick relay for controlling said indication device.

4. In railway traffic direction controlling apparatus manually controlled for governing traffic movements in both directions over a given stretch of main track divided into a first and a second section and including a given signal for governing traffic movements in a given direction entering said stretch through said first section, the combination comprising, a polarized reverse traffic relay, a circuit for energizing said reverse traffic relay by current of reverse polarity if said given signal is controlled to indicate proceed and is then controlled to indicate stop after a train moving in said given direction has left said first section but before it has left said second section, a second circuit for energizing said reverse traffic relay by current of normal polarity if said traffic direction controlling apparatus is then arranged for a traffic movement in the opposite direction through said first section while said train still occupies said second section, and indication means controlled by said reverse traffic relay.

5. In railway traffic direction controlling apparatus for governing traffic movements in both directions over a given stretch of track divided into a first and a second and a third section arranged in that order, including a given signal for governing traffic movements in a given direction onto said stretch through said first section, including a second signal for governing traffic movements in the opposite direction into said second section from an auxiliary track, the combination comprising, a polarized reverse traffic relay, a circuit for energizing said reverse traffic relay by current of reverse polarity if said first signal is controlled to indicate proceed and is then controlled to indicate stop after a train moving in said given direction has left said first section but before it has left said third section, a second circuit for energizing said reverse traffic relay by current of normal polarity if said traffic direction controlling apparatus is then arranged for a traffic movement in said opposite direction through said first and second sections while said train still occupies said third section, and means controlled by said reverse traffic relay for energizing indication means at a remote point or for clearing said second signal according as said reverse traffic relay is energized by said first or said second circuit.

6. In railway traffic direction controlling apparatus manually controlled for governing traffic movements in both directions over a given stretch of track, including a polarized traffic relay which upon becoming energized by current of normal polarity closes a normal polar contact for controlling traffic movements in a given direction over said stretch and which upon becoming energized by current of reverse polarity closes a reverse polar contact for controlling traffic move-

ments in the opposite direction over said stretch, including a signal for governing traffic movements in said given direction over said stretch, the combination comprising, a second polarized relay which upon becoming energized by current of reverse polarity effects the clearing of said signal and which upon becoming energized by current of normal polarity effects the return of said signal to the stop condition, means controlled by a normal polar contact of said first polarized relay for energizing said second polarized relay by current of either normal or reverse polarity, and means controlled by a reverse polar contact of said first polarized relay for energizing said second polarized relay by current of normal polarity only.

7. In railway traffic direction controlling apparatus manually controlled for governing traffic movements in both directions over a main track stretch connected at a switch intermediate its ends with an auxiliary track, the combination comprising, a polarized relay, a reverse circuit for energizing said polarized relay by current of reverse polarity while a train moving over said main track stretch in a given direction occupies said main track stretch in said given direction beyond said switch, a normal circuit which can then be closed for energizing said polarized relay by current of normal polarity if said traffic direction controlling apparatus is then controlled for governing traffic movements in the opposite direction over said main track stretch, indication means at a remote point controlled by a reverse polar contact of said polarized relay, and means controlled by a normal polar contact of said polarized relay for directing a train to move in said opposite direction from said auxiliary track over a portion of said main track stretch which is in said opposite direction from said switch.

8. In a railway traffic direction controlling apparatus for governing traffic movements in both directions over a main track stretch connected at a switch intermediate its ends with an auxiliary track, the combination comprising, a polarized relay, manually controllable means for energizing said polarized relay by current of reverse polarity if said main track stretch is occupied by a train moving in a given direction, manually controllable means for then energizing said polarized relay by current of normal polarity, indication means at a remote point controlled by a reverse polar contact of said polarized relay, and means controlled by a normal polar contact of said polarized relay for directing a train to move from said auxiliary track in the opposite direction over said main track stretch while a first train occupies said main track stretch in said given direction from said switch.

9. In railway traffic direction controlling apparatus for governing traffic movements in both directions over a given stretch of main track divided into a first and a second and a third section arranged in that order and including a switch for traffic movements from an auxiliary track into said second section and thence into said first section, including manually controllable means for at times directing traffic movements in a given direction into said stretch through said first section, the combination comprising, a circuit which becomes closed in response to said manually controllable means being arranged for directing a traffic movement in said given direction into said stretch and then being controlled to indicate stop after a train moving in said given direction has left said first section but before it has left said third section, a second circuit which becomes closed in response to said traffic direction controlling apparatus being then arranged for a traffic movement in the opposite direction through said second and first sections while said train still occupies said third section, means controlled by said second circuit for directing a traffic movement from said auxiliary track to said second section, and indication means controlled by said first circuit.

10. In railway traffic direction controlling apparatus for governing traffic movements in both directions over a given stretch of track divided into a first and a second and a third section arranged in that order, including a given signal for governing traffic movements in a given direction onto said stretch through said first section, including a second signal for governing traffic movements in the opposite direction into said second section from an auxiliary track, the combination comprising, a circuit which becomes closed in response to said first signal being controlled to indicate proceed and then being controlled to indicate stop after a train moving in said given direction has left said first section but before it has left said third section, an indication device controlled by said circuit for indicating that said traffic direction controlling apparatus may be manually controlled for governing a traffic movement in said opposite direction, a second circuit which becomes closed if said traffic direction controlling apparatus is then manually controlled for governing a traffic movement in said opposite direction while said train still occupies said third section, and a second indication device controlled by said second circuit for indicating that said second signal may then be cleared by manually controllable means.

HENRY S. YOUNG.
